THERMOCHROMIC REFRIGERATOR TEMPERATURE INDICATOR

Philip L. Van Kersen, P.O. Box 40423,
Indianapolis, Ind. 46204

Filed Jan. 10, 1975, Ser. No. 540,107

Term of patent 14 years

Int. Cl. D10—04

U.S. Cl. D10—57

Fig. 1

Fig. 2

Fig. 3

FIG. 1 is a front view of an embodiment of a thermochromic refrigerator temperature indicator, showing my new design.

FIG. 2 is a rear view thereof.

FIG. 3 is a side view thereof, the opposite side being a mirror image of that shown.

I claim:

The ornamental design for a thermochromic refrigerator temperature indicator, as shown.
